UNITED STATES PATENT OFFICE.

HENRY E. LINDQUIST, OF BOSTON, MASSACHUSETTS.

CARTRIDGE-CASE FOR ARTILLERY-SHELLS.

1,233,071.

Specification of Letters Patent. Patented July 10, 1917.

Application filed September 7, 1915. Serial No. 49,410.

To all whom it may concern:

Be it known that I, HENRY E. LINDQUIST, citizen of the United States, and resident of Boston, Massachusetts, have invented certain 5 new and useful Improvements in Cartridge-Cases for Artillery-Shells, of which the following is a specification.

This invention relates to artillery shells, and more particularly has reference to the 10 container or casing which holds the firing charge for impelling the shell from the gun.

Heretofore it has been the practice to make these cases of sheet brass which are formed into shape by successive drawing operations and which are then machined to size, thus involving a considerable expenditure of labor besides requiring a relatively expensive material which is also subject to considerable expansion with changes in temperature.

It is the object of the present invention to produce a charge-container or cartridge casing for artillery shells which shall be free from the principal objections and shortcomings heretofore experienced in this class of articles. To this end the invention comprises essentially a cartridge casing for artillery shells whose main portion comprises a tubular member of extremely hard dense 30 vulcanized fiber whose exterior is turned down to appropriate taper to fit the bore of the gun, and whose rear end is formed to have interlocking engagement with a metallic cap which closes the rear end.

This and other features of the invention will be more particularly explained herein-after and defined in the claims hereto annexed.

In the accompanying drawings I have 40 illustrated preferred forms of embodying the principle of this invention, in which,

Figure 1 is a central section of a shell embodying this invention.

Fig. 2 is a similar view of a slightly modified form of the invention.

I am aware of the fact that cartridges for small arms containing charges of powder and shot have been made of heavy cartridge paper as well as of metal, but such material 50 is of no practical use for artillery shells, both because it is not practical to give them the requisite taper to fit guns of larger caliber, and because this material does not possess sufficient strength for such use, and furthermore because of its easy deformation or distortion from shape. For these and other

reasons, the expensive and laboriously made brass shells form the only cartridge cases for artillery shells heretofore used.

I have discovered that it is possible to produce a highly satisfactory cartridge from a cylindrical tube formed of very hard dense vulcanized fiber which has been soaked for a sufficient length of time to eliminate all, or substantially all, of the acid or free chemical ingredient.

This tubing is made over a cylindrical mandrel in the usual manner but of a uniform diameter and having a thickness to allow the exterior to be turned down to the proper taper to fit the breech portion of the gun into which it is to be inserted.

It is especially important that the laminated fiber be made extremely hard and dense and that before the drying process the tubing shall be subjected to a long and thorough soaking to eliminate as much as possible all free chemical agents or acids, after which it is subjected to a thorough drying.

When the tube is thoroughly dry, the exterior is then turned down in a lathe in order to fit the bore of the gun.

In the drawings *a* designates the tubular casing turned down with the requisite external taper, and it will be observed that at 85 its rear end the tube is reduced in diameter and is provided with a heavy screw-thread, as shown at *a*¹ so as to adapt it to receive the internal screw-threaded brass or metallic cap *b*. The fit at this point should be a 90 close one, and, therefore, it may be advantageous to heat the metallic cap *b* somewhat above atmospheric temperature before screwing it upon the rear end of the tubing *a*, so that the shrinkage on cooling will make 95 a very snug fit.

To stiffen and reinforce the forward portion of the cartridge casing, I may in the case of the larger calibers cut away the material, as at *a*², to receive a close-fitting reinforcing band or ring *c* which is shrunk on at this point.

The tubing *a* may advantageously be water-proofed by the application of paraffin or other suitable water-proof coating and 105 particularly at the point of contact with the metal cap so that in case there should be a sufficient residuum of chemical reagents in the interior of the fiber when it has been machined, this coating will protect the metal 110 parts against corrosion from such chemicals.

In Fig. 2 I have shown a slightly modified form of the cartridge casing in which the rear end of the tubing *a* is cut away on the interior, as shown at *a*², in order to 5 receive an external screw-threaded cap member *b*¹.

In both cases, the shell or projectile *d* is shown inserted in the forward ends of the respective cases.

10 Since ordinary grades of the vulcanized fiber cannot satisfactorily undergo the machining operations required for this construction, and since, moreover, they usually contain too large a percentage of the chemical 15 reagents according to the vulcanized portions, it is of great importance that the tubing used be formed of a very hard dense grade and that the free chemicals shall be substantially eliminated to prevent corrosion.

20 It will, of course, be understood that the term "vulcanized fiber" employed herein has reference to that product which is obtained by the process of treating cotton fiber or 25 rag stock by chemical salts and other reagents to convert it into cellulose by proc-

esses of treatment well known to those skilled in that particular art.

What I claim is:

1. A cartridge casing for artillery shells 30 embracing in its construction an integral tube of hard vulcanized fiber substantially free from acid or salts, whose exterior is turned to a taper to fit the corresponding part of the bore of the gun, and a metallic 35 cap firmly secured to the rear end of said tubing, substantially as described.

2. A cartridge case for artillery shells 40 embracing an integral tube of hard vulcanized fiber whose mass is substantially free from chemical reagents whose interior surface is cylindrical and whose exterior surface is turned to an appropriate taper, the rear end of said tubing being formed with a screw-thread, and a metallic cap arranged 45 to fit the rear end and having screw-threads formed to engage and interlock with the threads on said tube, substantially as described.

In witness whereof, I have subscribed the 50 above specification.

HENRY E. LINDQUIST.
